UNITED STATES PATENT OFFICE

145,692

DESIGN FOR A LUBRICATING EQUIPMENT CABINET

Arthur M. Fitzpatrick, Jr., Detroit, Mich., assignor to Stewart-Warner Corporation, Chicago, Ill., a corporation of Virginia

Application October 26, 1945, Serial No. 123,218

Term of patent 14 years

(CL. D52—2)

To all whom it may concern:

Be it known that I, Arthur M. Fitzpatrick, Jr., a citizen of the United States, residing at Detroit, in the county of Wayne and State of Michigan, have invented a new, original, and ornamental Design for a Lubricating Equipment Cabinet, of which the following is a specification, reference being had to the accompanying drawing, forming part thereof.

Fig. 1 is a perspective view showing the top and front of a lubricating equipment cabinet embodying my new design; and

Fig. 2 is a perspective view showing the top and rear thereof.

I claim:

The ornamental design for a lubricating equipment cabinet, substantially as shown.

ARTHUR M. FITZPATRICK, JR.
